LOCK-ALARM COMBINATION

Herman H. Kempf, Garden City, N. Y., assignor
to Abe April, New York, N. Y.

Application May 27, 1949, Serial No. 95,649

8 Claims. (Cl. 116—14)

1

This invention relates in general to a lock-alarm combination and has as one of its objects the provision of an efficient, practical, economical combined closure fastener and alarm which is operable by the closure fastener when the door is being opened against the pull of the fastener.

It is a further object of the present invention to combine a chain-door fastener with an alarm such that an attempt to open the door will cause the chained bolt to slide a plate and effectuate thereby the ringing of an alarm.

Heretofore, it has been the practice to employ a bent wire operable by the movement of the chained bolt to cause a bell to ring. However, it has been found that such a device is not efficient and positive in its action. By providing a sliding plate having a cam which makes direct contact with the stem of a bell, the heretofore existing disadvantages have been overcome.

The above and other objects and advantages of the invention will appear as the description proceeds, it being understood, however, that it is not intended that the invention be limited to the exact details described herein which illustrate the preferred mode of carrying out the invention; and it is intended that there be included as part of the invention, such obvious changes and modifications thereof as would occur to a person skilled in the art to which this invention pertains and which would fall in the scope of the claims.

In the drawings:

Fig. 1 is a front elevational view of a portion of a door and its frame having applied thereto a combined closure fastener and alarm according to the invention;

Fig. 2 is a side elevational view of Fig. 1;

Fig. 3 is a sectional view taken on line 3—3 of Fig. 1;

Fig. 4 is a transverse sectional view somewhat similar to Fig. 3, but showing the door slightly ajar and the chained bolt in a different position;

Fig. 5 is a fragmentary view of Fig. 1, but showing the chained bolt in another position; and

Fig. 6 is a sectional view taken through line 6—6 of Fig. 1.

Referring now more particularly to the drawings, there is disclosed a door 10 and a frame member 11 opposite the free side 12 of the door; the door being hinged at its opposite side in the usual manner. Secured to the frame member 11 by means of screws 14 is an anchor plate 15 having at its upper end a slot 16. Secured to plate 15 as by means of a looped member 17 is a chain 18 to which is pivoted, by means of another loop

member 19, a bolt 20 having an annular groove 21. The recess or slot 16 is adapted to receive the bolt 20 when the latter is not in use to fasten the door. Secured to door 10 opposite plate 15 by means of screws 25 is a frame 26 having a perimetric flange 27 whereby to provide a space 29 between the front 28 of the frame and the door. Operable within the said space 29 is a slide plate 30 having a substantially wing-shaped cam slot 31. The ends of cam slot 31 project downwardly and slightly inwardly as indicated at 32a and 32b and from these ends the slot curves downwardly towards its center forming a concavity 33. Directly above concavity 33 the slot is arched as indicated at 34, so that the center portion of the slot is sufficiently large to accommodate the forward reduced portion 20a of the bolt 20 in order that the latter may project in the slot 31, with the head portion 20b of bolt 20 projecting outwardly and the channel or groove 21 of bolt 20 adapted to ride on the perimetric wall of slot 31. Slide plate 30 has an offset lug or like projection 35 extending from the center portion of its upper edge 36. Lug 35 projects through a slot or opening 37 of frame member 26, slot 37 being slightly longer than the lug 35 to permit longitudinal movement thereof. Lug 35 has a cam face 38 substantially V-shaped. Secured to a bracket 39 extending above frame 26 and by means of rivets 40 or the like is a conventional bell or alarm 41 having a stem or pin 42 projecting downwardly therefrom. Stem 42 slides in a sleeve 43. The upper end of stem 42 engages a member 44 of the conventional bell-ringing mechanism (not seen), while the lower end of stem 42 is provided with a slotted head 45, the slot of which engages the cam face 38 of lug 35. The operation of the device is as follows: Let it be assumed that it is desired to bolt the door in its closed position as seen in Fig. 1; then the bolt 20 is inserted in the slot 31 through the enlarged center opening O thereof and slid to the left along the slot, the said bolt finding itself at the downwardly projecting end 32a thereof. In an attempt to open the door against the pull of the closure-fastener, the bolt 20 on chain 18, which is held captive by the plate 15, will force the slide plate 30 to the right thereby causing stem 42 of the bell to ride up the incline of the cam face 38 of lug 35 thereby depressing the stem against the member 44 of the bell mechanism and causing the bell to ring. Now, let it be assumed that it is desired to leave the door slightly ajar, but at the same time bolted or to permit the door to be slightly opened by someone within the house

and yet keep the door bolted, then the bolt 20 is shifted into the end 32b of the slot. Now, if an attempt is made, say by an intruder, to force open the door beyond that limited by the length of the chain, then the plate will again be caused to slide by the bolt 20 in the manner heretofore described. The lug 35 is provided with two inclined surfaces which form the V-shaped cam so that the closure fastener together with its alarm may be employed at either the right or the left of the anchor plate 15.

The shape of slot 31 permits the bolt or stud 20 to be shifted from end 32a to end 32b to lengthen the chain 18 and thereby permit a person within the house to peek through the space between the slightly-opened door and the frame member 11. The slot 31 is undercut as shown by the numeral 32. This undercut is particularly provided at the downward-projecting ends 32a, 32b of slot 31 producing a wedging action with the bolt or stud 20 to prevent the latter from accidentally slipping out of the particular end it engages and sliding along the entire slot or falling out of the slot as it passes the enlarged central portion O. As clearly seen, the slot 31 substantially diverges from its central portion and its projections 31a, 31b are not only downwardly directed but, as heretofore stated, are inwardly directed to prevent the stud or bolt 20 from sliding up therefrom and along slot 31. The ends 30a of sliding plate member 30 which project beyond slot 31 are adapted to abut against the respective rearwardly-directed end walls 27 of frame 26, thus limiting the sliding movement of plate member 30. It is apparent that the device may be employed with either a right-handed hinged door or a left-handed hinged door.

From the foregoing description taken in connection with the accompanying drawing, it is apparent that an improved, simple, practical and inexpensive device for the purpose intended is provided. It is apparent however that immaterial changes and modifications may be made by skilled persons without departing from the true spirit and scope of the invention as outlined in the appended claims.

I claim:

1. In a combined closure-fastener and signalling device, the combination of a closure fastener comprising a slidable member, means for operably mounting said member on a door, said member having a cam element attached thereto and having a slot in said member, a flexible member, means for securing said flexible member to a structural part adjacent said door, a stud connected to said flexible member, said stud being slidably held in said slot to shift said slidable member when a pull is exerted on said flexible member, and signalling means having a movable projection for actuating the signal, said projection being in position for engagement with said cam element to be moved thereby.

2. In a combined closure-fastener and signalling device according to claim 1, wherein said means for operably mounting said slidable member comprises a frame slidably mounting said

slidable member, said frame having a slot through which said cam element projects.

3. In a combined closure-fastener and signalling device according to claim 1 wherein said cam element where it is engaged by said projection is substantially V-shaped.

4. In a combined closure-fastener and signalling device, the combination according to claim 1 wherein the slot in said slidable member comprises a central portion and two portions substantially diverging from said central portion, said diverging portions having means in the ends thereof acting as respective abutments for the stud when the latter is inserted in said slot, to detachably hold the same in the slidable member to cause said member to be pulled by the stud.

5. In a combined closure-fastener and signalling device according to claim 4 wherein said stud has a groove adapted to ride on the perimetric wall of said slot and said central portion of said slot is enlarged to accommodate the forward part of said stud, and wherein said means in the ends of the slot are downwardly and inwardly-directed to form a shoulder for detachably holding the stud in said slidable member to cause said member to slide.

6. In a combined closure-fastener and signalling device, the combination of a slidable member, means for operably mounting said member on a door, said member having a cam element and a slot, a flexible member, means for securing said flexible member to a structural part adjacent said door, a bolt connected to said flexible member, said bolt being adapted to be slidably retained in said slot and to slide said slidable member when a pull is exerted on said flexible member, signalling means having a reciprocatable projection, said projection being in engagement with said cam element, said means for mounting said slidable member comprising a frame providing a space between it and said door for sliding movement of said slidable member.

7. In a combined closure-fastener and signalling device according to claim 6 wherein said frame has rearwardly-directed end walls limiting the sliding movement of said sliding member.

8. In a combined closure-fastener and signalling device according to claim 6 wherein said cam element where it is engaged by said projection has a V-shaped face.

HERMAN H. KEMPF.
